UNITED STATES PATENT OFFICE.

FRANCIS W. DRAPER, OF RICHMOND, INDIANA, ASSIGNOR TO THE STARR PIANO COMPANY, OF RICHMOND, INDIANA, A CORPORATION OF INDIANA.

AUTOMATIC TRACKER.

1,138,461.

Specification of Letters Patent.

Patented May 4, 1915.

Application filed April 26, 1913. Serial No. 763,829.

To all whom it may concern:

Be it known that I, FRANCIS W. DRAPER, a citizen of the United States, residing at Richmond, in the county of Wayne and 5 State of Indiana, have invented certain new and useful Improvements in Automatic Trackers; and I do hereby declare the following to be a full, clear, and exact description of the invention, such as will enable 10 others skilled in the art to which it appertains to make and use the same.

This invention relates to tracker devices for player pianos; and has for an object to provide means for automatically readjusting 15 the relation between a traveling music sheet and a tracker bar when the desired alinement has been interrupted, and means for setting the adjusting means manually to compensate for shrinking or swelling of the 20 music sheet and also the improper or inaccurate positioning of the perforations upon the sheet.

A further object of the invention is to provide a tracker bar of substantially the 25 usual and ordinary form preferably rigidly connected with the music box and with a rigid frame surrounding the music box carrying the music rolls and operating mechanism with improved pneumatic means for 30 moving the rigid frame and the carried parts relative to such tracker bar.

A further object of the invention is to provide means for permitting the manual independent adjustment of the valves relative 35 to the sliding member.

With these and other objects in view the invention comprises certain novel constructions, combinations and arrangement of parts as will be hereinafter more fully described and claimed.

In the drawings: Figure 1 is a view of a conventional music box in front elevation showing the improved tracking controlling device connected therewith. Fig. 2 is a top 45 plan view of the music box with the attachment carried thereby. Fig. 3 is a view in front elevation of the rigid frame carrying the music rolls and the pneumatic control therefor. Fig. 4 is a view of the outside of 50 the music box in end elevation showing the tracker attachment connected therewith. Fig. 5 is a transverse sectional view through the music box and attachment taken on line 5-5 of Figs. 1 and 2. Fig. 6 is a detail 55 view of the manual adjusting mechanism re-

moved from the music box. Fig. 7 is a detail view in plan of one of the valves as indicated by arrow 7 at Figs. 1 and 6. Fig. 8 is a detail view of one of the valves in end elevation looking in the direction indicated by arrow 8 in Fig. 6. Fig. 9 is a view of one of the valves in rear elevation as indicated by arrow 9 at Fig. 5. Fig. 10 is a view in perspective of one of the valve blocks. Fig. 11 is a detail view of the pivoted connection between the side member and its controlling lever as indicated by arrow 11 at Figs. 1 and 6.

Like characters of reference designate corresponding parts throughout the several views.

The improved tracking mechanism which forms the subject matter of this application is adapted to be associated with a music box of a player piano indicated conventionally at 15 having a tracker bar 16 both of substantially the usual and ordinary form.

Surrounding the music box preferably upon the exterior thereof is a rigid frame comprising the end cross bars 17 and 18 and top and bottom rods 19 and 20 which frame carries the music spool 21 and the winding roll 22. This spool and roller are carried in substantially the usual manner by sleeves 23 and 24 having spring connections and trunnions 25 and 26 by which such spool and roller are controlled in substantially the usual and ordinary manner. The connections of the music spool and music roll do not differ from the ordinary means of connecting such spool and roll with the music box except that the connections extend loosely through the cheek plates of the music box and are carried directly by the cross bars 17 and 18. Connected also with the 95 cross bar 18 is the driving mechanism indicated as a whole at 27 in Figs. 1 and 2, such driving mechanism forming no essential part of the present invention.

As indicated at Fig. 1 the rigid frame carrying the music spool 21 and the music roll 22 is slidable relative to the music box and the tracker bar 16 so that the music sheet may be moved transversely of its width and longitudinally of the tracker bar to readjust the alinement of the sheet relative to the bar. To effect such movement a double pneumatic 28 is provided, such pneumatic having on opposite sides movable walls 29 and 30 connected by a cross bar 31 110

so that said walls 29 and 30 move together. The wall 29 is connected with the rigid frame through the medium of a link 32 and connecting clips 33 and 34. It is obvious, therefore, that when the walls 29 and 30 of the pneumatic move they move therewith the rigid frame and the music spool and music roll. To provide for such movement of the walls of the pneumatic the said pneumatic is connected by means of a flexible tube 25 with the ordinary exhaust chest of the player piano so that the said double pneumatic is under constant exhaust in the usual and ordinary manner. Adjacent the tracker bar 16 a rod 36 is slidably mounted carrying blocks 37 and 38 adjustable thereon, such adjustment being effected by means of knurled screws 39 and 40 respectively. The blocks 37 and 38 are similar but reversed and a description of one will serve as a description of both. The block 38 is provided with a port 41 communicating with a nipple 42 which extends through the cheek plate and has connected therewith a flexible pipe 43 extending to one side of the pneumatic. The other block 37 has a flexible tube 44 extending to the other side of the pneumatic.

The block 38 is provided with a valve member 45 pivoted thereto as at 46 with a spring 47 adapted to hold the valve normally to seat over the port 41. The block also carries an upstanding wing 48 normally in alinement with the edge of the music sheet as indicated by its alinement with the ends of the music spool and music roll as shown in Fig. 1. A wing 48' is similarly carried by the block 37 in similar alinement. It is obvious that under normal conditions the music sheet passing over the tracker bar will have its opposite edges engaging the wings 48 and 48', that any movement of the sheet in either direction will serve to actuate one of the valves and that the actuation of such valve to open its corresponding port will actuate the pneumatic to move the frame spool and roll in such direction as to restore the alinement.

It will be apparent that as the relation of the perforation to the tracker bar varies under different conditions of cutting and atmospheric conditions the adjustment must be restored by a manual sliding of the blocks 37 and 38 along the rod 36 or that the entire rod must be moved to move both of such blocks and their accompanying valves in unison. The sliding of the said rod 36 and the accompanying valves is accomplished by means of the lever 49, pivoted to the cheek plate at 50 and pivotally connected with the rod 36 by bending the top of said lever at right angles as indicated at 51 and providing the rod 36 with a collar 52, a screw 53 being inserted through such bent over portion 51 and the collar 52 and abutting 65 against the rod.

A rod 54 is slidably mounted in the bottom of the music box and pivotally connected with the lever 49 as at 55 with a manual lever 56 pivoted in the music box as indicated at 57 and also pivotally connected at 58 with the rod 54 as shown particularly at Fig. 6. It will be apparent, therefore, that as the manual lever 56 is moved in either direction the sliding rod 36 will also be moved in the opposite direction as indicated by dotted lines in Fig. 1 to move its valve members to restore the normality of the sheet and tracker bar.

It will, therefore, be apparent that the valves will not only be operated by the displacement of the music sheet under ordinary conditions but the rod carrying such valves may be manually operated by the manual lever 56 at will of the player. Such valves may also be adjusted relative to the rod by means of the screws 39 and 40. By this adjustment wide range of adjustment of the parts is accomplished.

I claim:

1. The combination with a tracker bar, of a rigid frame embracing the tracker bar, music rollers carried by the rigid frame upon opposite sides of the tracker bar, pneumatic means for moving the rigid frame and music rollers, a sliding member mounted adjacent the tracker bar, valves carried by the sliding member, and in line with the ends of said rollers and means to manually adjust the sliding member relative to the tracker bar.

2. The combination with a tracker bar rigidly mounted, of a rigid frame surrounding the tracker bar, music rollers carried by the rigid frame upon opposite sides of the tracker bar, pneumatic means for shifting the rigid frame and music rollers longitudinally of the tracker bar, a rod adjacent and slidably relative to the tracker bar, valves carried by the rod in line with the ends of said rollers and adapted to control the pneumatic, and means to manually slide the rod independently of the tracker bar and music rollers.

3. The combination with a tracker bar; of music rollers upon opposite sides of the tracker bar, pneumatic means for simultaneously moving the music rollers relative to the tracker bar, a double pneumatic a rod mounted adjacent the tracker bar, valve blocks carried by the rod, wings carried by the blocks in alinement with the opposite ends of the music rollers, means connecting the valves with the pneumatic, and manual means to slide the rod longitudinally of the tracker bar.

4. The combination with a tracker bar, of music rollers disposed upon opposite sides of the tracker bar, pneumatic means for adjusting the alinement between the tracker bar and the music rollers, a rod slidably

mounted adjacent the tracker bar, valve blocks carried by the rod, in alinement with the opposite ends of the music rollers, means for controlling the valves, and manual means 5 for sliding the rod relative to the tracker bar and rollers.

5. The combination with a tracker bar, a movable frame, music rollers therein on opposite sides of the tracker bar, and means to 10 automatically adjust the position of the frame and music rollers with respect to the tracker bar; of a rod slidably mounted relative to the tracker bar, valve members on the rod, wings carried by said members and 5 normally in alinement with the opposite ends of the music rollers, a second slidably mounted rod, a manual lever for moving it, and a rock lever connecting the two rods.

6. The combination with a tracker bar; of music rolls on opposite sides of the tracker 20 bar, means for simultaneously moving the music rolls relative to the tracker bar, a double pneumatic, a rod mounted adjacent the tracker bar, valve blocks carried by the rod in alinement with the opposite ends of 25 the music rolls, tubes connecting the valves with the pneumatic, and a hand lever connected with the rod for moving it longitudinally of the tracker bar independent of said pneumatic.

In testimony whereof I affix my signature in presence of two witnesses.

FRANCIS W. DRAPER.
